United States Patent Office.

JOHN ABENDROTH, OF NEW YORK, N. Y.

Design No. 2,655, dated May 21, 1867.

DESIGN FOR A COOK'S STOVE.

The Schedule referred to in these Letters Patent and making part of the same.

TO ALL WHOM IT MAY CONCERN:

Be it known that I, JOHN ABENDROTH, of the city, county, and State of New York, have invented a new and original design for a Cook Stove; and I do hereby declare that the following is a full, clear, and exact description thereof, which will enable others skilled in the art to understand the same, reference being had to the accompanying drawing, forming part of this specification.

This invention relates to a new and original design for ornaments for a cook stove, which I term the "Cotton Plant," the name having its origin in the design, which consists of a cotton plant, or a portion thereof, in relief on the panels of the doors and other parts of the stove.

A perspective view of the stove is shown in the illustration or drawing.

A represents the panels of the doors with a portion of the cotton plant in relief upon them; *a* representing the stem, and *b* the bolls in a closed state, and *c* the open bolls, and *d* the leaves.

Having thus described my invention, I claim as new, and desire to secure by Letters Patent—

A new and original design for ornaments for a cook stove, consisting of a portion of a cotton plant in relief on the panels of the doors, as shown and described.

JOHN ABENDROTH.
